UNITED STATES PATENT OFFICE.

HARRY B. HARLOW, OF ALTON, ILLINOIS, ASSIGNOR TO COMMONWEALTH STEEL COMPANY, OF ST. LOUIS, MISSOURI, A CORPORATION OF NEW JERSEY.

MOLDING APPARATUS.

1,401,601.

Specification of Letters Patent. Patented Dec. 27, 1921.

Application filed June 14, 1920. Serial No. 388,967.

To all whom it may concern:

Be it known that I, HARRY B. HARLOW, a citizen of the United States, residing at Alton, in the county of Madison and State 5 of Illinois, have invented a new and useful Improvement in Molding Apparatus, of which the following is a specification.

My invention relates to molding apparatus, and has for its object to provide improved means in combination with the molding form for a casting for holding down the cover core, the said means in so doing being automatically locked to the said form and adjustable relatively to the plane of the top 15 surface and position of the cover core.

My invention which is especially applicable to the mold for which Letters Patent of the United States were granted to Andrew F. Howe, June 20, 1911, No. 995,968, consists in features of novelty as hereinafter described and claimed, reference being had to the accompanying drawing forming part of this specification, whereon,

Figure 1, is a top plan view of a molding 25 form and mold having a plurality of cover cores with my invention applied thereto; Fig. 2, a vertical transverse section therethrough on line 2, 2, in Fig. 1; Fig. 3, a top plan view to enlarged scale of a clamping bar and bearing plate forming parts 30 of my invention, and Fig. 4, a side elevation of the same.

Like letters and numerals of reference denote like parts in all the figures.

35 *a* represents a metallic molding form or flask which may be of any suitable configuration according to the nature of the desired casting, and is in the present case rectangular-shaped, open at the top and preferably closed 40 at the bottom, the outer sides or walls 1 of the form *a* being preferably channel-shaped in cross section with their flanges outward and united at the corners, while the inner sides 1' of the form *a*, which are outwardly 45 flanged at the top in a similar manner to the outer sides 1, are arranged parallel to the latter respectively, at a suitable distance therefrom so as to form an open rectangular-shaped space or well *b* in the middle 50 of the form *a* for the purpose hereinafter more particularly referred to.

From the inner face of each side 1, 1', respectively, at suitable intervals along the 55 same, projects a series of vertically ar-

the form *a* and preferably unite with the bottom member 3 from which project upward within and preferably entirely across the form *a* similar ribs 2'. On the upper edges of the ribs 2' is laid a base piece (or 60 series thereof) 4 composed of suitable baked molding material, which is adapted to support a series of outer and inner sectional blocks 5, 5', composed of suitable baked molding material and forming respectively 65 a corresponding part of the mold, the blocks 5, 5', being arranged in proper order within the form *a* conformably to the shape and configuration of the mold cavities 6, 6', while the spaces within the form *a* unoccupied 70 by the blocks 5, 5', are preferably filled with sand or other suitable material *x* which is lightly packed about the blocks 5, 5', in a similar manner to that described in the aforesaid patent, the whole forming a complete mold which is then covered by preferably a plurality of cover cores *c* composed of suitable baked molding material and of varying size and arrangement according to the configuration of the mold, 80 the cover cores *c* butting edgewise (or not) against each other as shown.

Projecting preferably outward from the outer and inner sides 1, 1', respectively of the form *a* immediately beneath and at a 85 suitable distance from the top flange thereof, is a rib 7 which preferably extends the entire length of the side; or if desired lugs or equivalent projections may be substituted for the rib 7. Vertically through the said 90 flange is formed at intervals along the same a preferably circular hole 8 and through the rib 7 (or corresponding lug or projection) opposite to each hole 8 is formed a similar hole 8'.

d represents (see particularly Figs. 3 and 4) an inverted L-shaped bar having its shank 9 preferably circular and somewhat diametrically smaller than the holes 8, 8' the overhanging member 9' of the bar *d* terminating at its depending end in a ball 10 which is adapted to engage in a correspondingly shaped socket 10' formed on the upper surface of a preferably rectangular-shaped bearing plate *e* which is adapted to bear 105 upon the cover core *c*.

For clamping either of the cover cores *c*, as for example the cover core *c* shown to the left in Figs. 1 and 2, the shank 9 of the bar *d* is inserted and dropped endwise through the 110

holes 8, 8', and as the bearing plate *e* is closing down upon the top surface of the cover core *c*, the shank 9 of the bar *d* is forced out of alinement and becomes jammed 5 against the opposing edges of the holes 8, 8', thereby automatically clamping the bearing plate *e* against the top of, and securely holding down the cover core *c*, the bearing plate *e* at the same time, owing to the ball and 10 socket joint thereof with the bar *d*, accommodating itself to any inequality of the top surface of the cover core *c*. If desired a tighter clamping of the bearing plate *e* to the cover core *c* may be effected by hammer 15 blows on the top of the shank 9 of the bar *d*. On striking the bar *d* laterally near the top its shank 9 will be disengaged and the bar *d* free for removal.

It will be here noted that in the present 20 case, the holes 8, 8', through the top flanges and ribs (or lugs) 7 of the outer sides 1 are shown respectively as being directly opposite to the centers of the corresponding outer cover cores *c*, and those of the inner sides 1' 25 diagonal to the centers of the inner cover cores *c*, the directions of the bars *d* being so indicated by dotted lines, but the bars *d* may be otherwise arranged in any desired direction according to the varying shapes and positions of the cover cores to be secured there- 30 by, and by having a well or open space 3 in the middle (or other convenient part) of the molding form *a* the bars *d* may be applied to those cover cores which otherwise 35 would be inaccessible to the ordinary sized bar.

I claim:—

1. In a mold, the combination with a molding form and a plurality of cover cores, 40 of individual means each adapted to independently secure a cover core to the form and to adjust itself to the plane of the top surface of its individual cover core.

2. In a mold, the combination with a molding form and a plurality of cover cores, 45 of individual means each adapted to independently clamp a cover core to the form and to adjust itself to the plane of the top

surface of its individual cover core and to the height of its individual cover core. 50

3. In a mold, the combination with a molding form and a plurality of cover cores, of individual means each adapted to independently clamp a cover core to the form, each of said means comprising an inverted 55 L-shaped bar, a bearing plate, and a universal joint between said bar and plate.

4. In a composite mold, a plurality of sectional mold blocks assembled in cooperative relation, a plurality of cover cores completing the sections of the mold, and individual clamping means for each of said cover cores. 60

5. In a composite mold, a mold form, a plurality of sectional mold blocks assembled in coöperate relation, a plurality of cover 65 cores completing the mold sections, and a plurality of clamps mounted on said form, each securing one of said cover cores and the adjacent mold blocks in assembled position.

6. In a composite mold, a mold form, 70 spaced horizontal flanges on the outside of said form, substantially alined holes in said flanges, a plurality of mold blocks assembled in mold forming relation within said form, a plurality of cover cores placed on said 75 blocks, and individual clamps removably mounted in each pair of said alined holes, each adapted to secure one of said cover cores and its associated mold blocks in position. 80

7. In a composite mold, a mold form having outside walls and inside walls spaced therefrom, and a bottom wall connecting said outside and inside walls, vertically spaced horizontal flanges on each of said 85 walls, a plurality of holes in said flanges arranged in pairs, the holes of each pair being in substantial vertical alinement, a plurality of mold blocks carried by said bottom wall between said outside and inside walls, a plurality of cover cores for said mold blocks, and individual cover core clamps detachably mounted in respective pairs of said holes, each adapted to secure one of said cover cores in position. 90

HARRY B. HARLOW.
